UNITED STATES PATENT OFFICE

ALBERT F. BREITENSTEIN, OF NEW HAVEN, CONNECTICUT, ASSIGNOR TO THE
GEOMETRIC TOOL COMPANY, OF NEW HAVEN, CONNECTICUT, A CORPORATION

GRINDING FIXTURE FOR THREAD-CUTTING CHASERS

Application filed October 25, 1929. Serial No. 402,534.

Heretofore the chamfers and the cutting-faces of threading-chasers, such as are used in self-opening die-heads and collapsing taps and kindred tools, have been ground in separate fixtures, involving considerable initial expense for the fixtures themselves and time and labor in transferring the chasers from one to the other for the respective chamfering and face-grinding operations.

The object of my present invention is to produce a single unitary fixture adapted to be set for these respective operations, so that after a given number or batch of chasers have had the chamfer-grinding operation performed upon them, the same fixture may be set for having the same lot of chasers ground upon their cutting-faces, or vice versa, the order or sequence of the two operations being immaterial.

My improved unitary fixture is thus adapted to the dual purpose of face-grinding, as well as chamfer-grinding.

With these ends in view, my invention consists in a grinding-fixture for thread-cutting chasers having a head swiveled to turn in a horizontal plane, a horizontal longitudinally-adjustable carrier-bar carried by the said head and adapted to be axially rocked in a vertical plane, and a chaser-holder carried by the said bar.

My invention further consists in a grinding-fixture having certain details of construction and combinations of parts as will be hereinafter described and pointed out in the claims.

With reference now to the drawings, Figs. 1 to 4 inclusive show my improved fixture as set for chamfer-grinding chasers of the milled-type—the common term employed for chasers having straight cutting-teeth.

In the accompanying drawings:

Fig. 1 is a view in front elevation of my improved fixture as set for grinding the chamfers of milled type thread-cutting chasers, the fixture being shown as mounted upon a suitable grinding-machine base;

Fig. 2 is a plan view thereof;

Fig. 3 is a view thereof in left-hand end elevation;

Fig. 4 is a transverse sectional view taken on the line 4—4 of Fig. 1;

Fig. 5 is a view of the fixture in front elevation as set for grinding the hook-like cutting-faces of certain chasers;

55

Fig. 6 is a view thereof in right-hand end elevation;

60

Fig. 7 is a detached view in end elevation of a milled type chaser with a hook-like cutting-face;

Fig. 8 is a face view thereof;

Fig. 9 is a face view of the fixture as set for grinding the chamfers of chasers having convex cutting-teeth;

Fig. 10 is a view thereof in left-hand end elevation;

65

Fig. 11 is a detached end view of such a chaser;

Fig. 12 is a face view thereof;

Fig. 13 is a plan view of my improved fixture as set for grinding the chamfers of chasers having concave cutting-teeth;

70

Fig. 14 is a view thereof in left-hand end elevation;

Fig. 15 is a detached view in end elevation of such a chaser;

75

Fig. 16 is a face view thereof; and

Fig. 17 is a detached plan view of the cylindrical carrier-bar of the fixture.

As herein shown, my improved fixture is provided with a base 20 adapted to be attached by bolts 21 to the sliding-table 22 of a grinding-machine of any approved type. The table 22 is mounted for longitudinal movement upon a sub-table 23 which, in turn, is mounted for transverse movement upon a bed 24. The base 20 is formed with an upstanding circular boss 25 having a flat upper face providing a bearing for the flat under face of a circular swivel-head 26 having a heavy centrally-depending trunnion 27 formed with an annular peripheral groove 28 receiving the pointed end of a locking-screw 29 having a wing-head 30, the trunnion 27 fitting within a bearing-opening 31 formed in and concentric with the upstanding boss 25. The trunnion, and hence the swivel-head 26, is held against upward displacement in the boss 25 by means of an anchoring-plate 32 secured to its lower face by screws 33, and

80

85

90

95

100

located in a recess 34 in the under face of the base 20, the opposite ends of the said plate being engaged with the upper wall of the said recess 34, as shown in Fig. 1 of the drawings.

- 5 When the swivel-head 26 is turned, the ends of the plate 32 sweep over the upper wall of the recess 34. Under this construction, the swivel-head 26, when unlocked, may be turned in either direction in the horizontal plane upon the upstanding boss 25 of the base 20. When set, it is locked against turning by the locking-screw 29.

To guide the user of the fixture in setting the swivel-head 26 at the desired angle with respect to the base 20, the upstanding boss 25 is furnished with a segmental scale 60 and the periphery of the swivel-head 26 with diametrically-opposite index-lines 61, as shown in Fig. 1.

- 20 The upper face of the swivel-head 26 is formed at one side of its center with a heavy and preferably integral mounting-block 35 having a horizontal cylindrical bearing-opening 36 and longitudinally split as at 37 to adapt it to be sprung by a clamping-screw 38 so as to grip a heavy cylindrical carrier-bar 39 in any desired position therein of rotary or longitudinal adjustment.

For the purpose of readily determining the longitudinal adjustment of the carrier-bar 39 in the mounting-block 35, it is provided upon its periphery with a longitudinal scale 40 which is read in connection with the smooth inner face 41, shown in Fig. 1, of the block.

- 35 The carrier-bar 39 is also provided with an index-line 42 (Fig. 2) which is read in conjunction with a segmental scale 43 formed upon the smooth outer face 44, shown in Fig. 3, of the block.

- 40 At the end of the carrier-bar opposite the scale 40 already described, it is formed with two pairs of diametrical holes 45 and 46, 47 and 48, the holes 45 and 47 being larger than their complementary holes 46 and 48. The holes 45 and 47 receive, according to the setting of the fixture, a mounting-bolt 49, while the holes 46 and 48 receive, according to the setting of the fixture, a stop-pin 50 adapted to be set into either hole, both (i. e., the holes 46 and 48) of which are provided with set-screws 51 for firmly holding the said stop-pin in place.

55 The holes 45 and 47 aforesaid provide for the rigid attachment to the bar in the horizontal or vertical position, as the case may be, of a chaser-holder 52 formed in its inner end and in one of its sides respectively with threaded bores 52^a and 52^b positioned at right angles to each other for the reception of the mounting-bolt 49, according to the desired position of the holder with respect to the bar 39. The said holder is bifurcated or split inward from its outer end by a deep centrally-located Y-shaped slot 53 enlarged at its outer end to form a chaser-receiving socket 54.

The chaser-holder 52 is thus provided with yielding clamping-arms 55 and 56 which are drawn together to grip a chaser in the socket 54 by a clamping-screw 57 having a wing-head 58 and passing laterally through the holder, as shown in Fig. 4.

In the use of my improved fixture for grinding the chamfers of milled type chasers in accordance with the set-up of the fixture, as shown in Figs. 1 to 4 inclusive, the chaser-holder 52 is fastened in a vertical position upon the cylindrical carrier-bar 39 by means of the screw 49 which is passed upward into its threaded bore 52^a through the diametrical hole 47 in the bar. The stop-pin 50 is set into the hole 48 and secured therein by its set-screw 51. A milled type chaser, such as 62 (Figs. 7 and 8), is now set into the socket 54, in which it is positioned by bringing its teeth into engagement with the adjacent face of the stop-pin 50. The clamping-screw 57 is now turned by its wing-head 58 to firmly clamp the chaser in this position. The swivel-head 26 is now unlocked and swung in a horizontal plane in one direction or the other (dependent upon whether the chaser is a right-hand or left-hand chaser) to set it to the clearance-angle at which it is desired to grind the chamfer, this setting of the swivel-head being determined by the reading of 95 diametrically-opposite index-lines 61 upon the swivel-head 26 with respect to a segmental scale 60 upon the boss 25 of the base 20. As soon as the swivel-head has been set, it is relocked by the screw 29. The setting of the swivel-head may, of course, be effected before the chaser 62 is mounted in the chaser-holder 52, or at any time before the grinding operation is started. The table 22 carrying the unitary fixture, is now moved so as to bring the chamfer of the chaser 62 into engagement with the periphery of a grinding-wheel 63. By means of the transversely-movable sub-table 23, the fixture is now transversely moved so as to pass the chamfer of the 105 chaser back and forth across the periphery of the grinding-wheel aforesaid. The chamfer-clearance angle of the chaser being operated upon is thus determined by setting the swivel-head 26 with respect to the base 20 and locking it in place by means of the screw 29. The desired slope of the chamfer-angle is secured in the usual manner by raising or lowering either the grinding-wheel 63 or the bed 24, or both, with respect to each other.

110 The chaser in the holder having had its chamfer 64 ground, is removed and replaced by a corresponding chaser, and so on, until all of the chasers of any given lot have been thus operated upon.

115 In order to grind the cutting-faces 65 of the chasers, the mounting-screw 49 is unscrewed from the chaser-holder 52 and the same turned down into a horizontal position, with its axis parallel with the carrier-bar 120 125 130

39, as shown in Fig. 5, and the screw 49 passed through the hole 45 therein and screwed into the threaded bore 52^b of the chaser-holder for rigidly mounting the same upon the carrier-bar 39. The stop-pin 50 is now removed from the hole 48 in the said bar and the chaser set into the socket 54 in the chaser-holder in the position shown in Figs. 5 and 6 and locked in place therein by the use of the clamping-screw 57. The carrier-bar 39 is now rocked in the vertical plane to the angle required for the cutting-face to be ground, this being gauged by means of the scale 43 on the mounting-block 35 and the index-line 42 (Fig. 2) on the bar. Of course, this setting of the bar at the angle desired may be effected at any time before the actual grinding is begun. At this time, as it will be understood, the swivel head 26 is set at zero and locked thereat. The sub-table 23 carrying the fixture is now moved laterally to cause the cutting-face 65 of the chaser to be brought into engagement with a side-face of the grinding-wheel 63. The sliding-table 22 is now reciprocated to cause the cutting-face of the chaser to move back and forth with respect to the side-face of the grinding-wheel.

The set-up of the fixture, as above described, for grinding the cutting-faces of the chasers, is substantially the same for all common forms of chasers, such as milled type chasers, Figs. 7 and 8; convex chasers, Figs. 11 and 12; and concave chasers, Figs. 15 and 16; and so on.

In order to use my improved fixture for grinding the chamfers of convex-toothed chasers (Figs. 11 and 12), which are primarily designed for use in collapsing taps, the carrier-bar 39 is appropriately positioned longitudinally in the mounting-block 35, as shown in Figs. 9 and 10. The chaser-holder 52 is fastened in vertical position to the said bar by means of the screw 49. A chaser is then clamped in position in the chaser-holder and brought to bear against the stop-pin 50. The bar 39 is now rocked in a vertical plane so as to cant the chaser-holder and chaser to the required angle to produce the desired chamfer-clearance angle and locked in such position. The table 22 is then moved longitudinally, carrying with it the unitary fixture, until the chamfer of the chaser is brought into contact with the periphery of the grinding-wheel 63. The screw 29 having been loosened to permit the swiveling in the horizontal plane of the head 26, the same is freely oscillated in the horizontal plane by the user of the fixture, who swings it by grasping the adjacent end of the carrier-bar, whereby the chamfer of the chaser is swung across the periphery of the grinding-wheel. The degree of convexity produced by such grinding is determined by the radial distance of the chamfer being ground from the vertical axis of the swivel-head 26. Thus, if

the carrier-bar 39 is so adjusted as to bring the chamfer near the said vertical axis, a very marked curvature will be ground upon the chamfer, whereas, if the said bar is adjusted longitudinally with respect to the swivel-head, so as to locate the chamfer remote from the vertical axis of the said head, a relatively slight convexity will be ground upon the chamfer.

To set my improved fixture for grinding concave-toothed chasers of the type shown in Figs. 15 and 16, the fixture is set, as shown in Figs. 13 and 14, so as to bring the chamfer 64 of the chaser in a position facing toward the vertical axis of the swivel-head 26. When the swivel-head is oscillated back and forth in the horizontal plane by the user, a concave grinding of the chamfer results.

It will be understood that the sequence of adjustments in setting the fixture to do its different kinds of work may be varied from the order herein set forth, it only being necessary that the ultimate adjustments be made before the cutting is begun. It may also be stated that with the smaller types of milled type chasers, they may have their cutting-faces ground by merely turning them in the chaser-holder itself, without resorting to detaching the same from the carrier-bar and re-locating it thereupon.

I claim:

1. A grinding-fixture for thread-cutting chasers having a disk-shaped head swiveled to turn in a horizontal plane, a horizontal longitudinally-adjustable carrier-bar extending diametrically over and carried by the said head and adapted to be axially rocked in a vertical plane, and a chaser-holder located above and carried by the said bar.

2. A grinding-fixture for thread-cutting chasers having a disk-shaped head swiveled to turn in a horizontal plane, a horizontal longitudinally-adjustable carrier-bar extending diametrically over and carried by the said head and adapted to be axially rocked in a vertical plane, and a removable chaser-holder located above and carried by the said bar.

3. A grinding-fixture for thread-cutting chasers having a disk-shaped head swiveled to turn in a horizontal plane and provided with an upstanding clamping-member formed with a horizontal cylindrical axial passage, a horizontal longitudinally-adjustable carrier-bar adapted to be clamped in the said passage so as to extend diametrically over the said head and adapted to be axially rocked therein in a vertical plane, and a chaser-holder located above and carried by the said bar.

4. A grinding-fixture for thread-cutting chasers having a disk-shaped head swiveled to turn in a horizontal plane, a horizontal longitudinally-adjustable carrier-bar extending diametrically over and carried by the said head and adapted to be axially rocked in a

70

120

125

130

vertical plane therein, and a chaser-holder located above and carried by the said bar and adapted to be reversibly secured thereto for presenting chasers in different positions to a grinding-wheel.

- 5 5. A grinding-fixture for thread-cutting chasers having a disk-shaped head swiveled to turn in a horizontal plane, a horizontal longitudinally-adjustable carrier-bar extending diametrically over and carried by the said head and adapted to be axially rocked therein in a vertical plane, and a removable chaser-holder located above and carried by the said bar and reversible in position thereon for 10 changing the presentation of the chasers with respect to a grinding-wheel, and removable means applied to the said bar independent of the said holder for gauging the position of a chaser therein.
- 15 6. A grinding-fixture for thread-cutting chasers having a head swiveled to turn in a horizontal plane, a horizontal longitudinally-adjustable carrier-bar carried by the said head, adapted to be axially rocked in a vertical plane therein and provided with a plurality of diametric sockets, a chaser-holder carried by the said bar and adapted to be reversibly attached thereto by means passing through one of the sockets therein, and a 25 gauge adapted to be mounted in the bar in one of the sockets therein, dependent upon the position of attachment of the holder thereto.
- 30 7. A grinding-fixture for thread-cutting chasers, comprising a base adapted to be secured to the table of a grinding-machine and formed with a vertical cylindrical socket, a swiveled disk-shaped head provided with a depending trunnion fitting within the said 35 socket with capacity for turning movement in a horizontal plane with respect to the said base, a horizontal longitudinally-adjustable carrier-bar extending diametrically over and carried by the said swiveled head and adapted 40 to be axially rocked with respect thereto in a vertical plane, and a chaser-holder located above and carried by the said bar.

- 45 8. A grinding-fixture for thread-cutting chasers, comprising a base adapted to be secured to the table of a grinding-machine and formed with a vertical cylindrical socket, a swiveled disk-shaped head provided with a depending trunnion fitting within the said 50 socket with capacity for turning movement in the horizontal plane with respect to the said base, means for locking the swiveled head in various positions of horizontal adjustment with respect to the said base, a horizontal longitudinally-adjustable carrier-bar 55 extending diametrically over and carried by the said swiveled head and adapted to be axially rocked with respect thereto in a vertical plane, means for locking the said bar in the said swiveled head in any one of its 60 positions of axial and longitudinal adjust- 65

ment therein, and a chaser-holder carried by the said bar.

9. A grinding-fixture for thread-cutting chasers having a head swiveled to turn in a horizontal plane, a horizontal longitudinally-adjustable carrier-bar carried by the said head and adapted to be axially rocked in a vertical plane, means for locking the said head and carrier-bar in any one of their adjusted positions, and a removable chaser-holder carried by the said bar and entered by two threaded bores arranged at right angles to each other for the reception of a bolt by means of which it is rigidly secured in either one of two positions with respect to the bar for changing the presentation of a chaser held in it to the action of the grinding-wheel.

In testimony whereof, I have signed this specification.

ALBERT F. BREITENSTEIN.
